UNITED STATES PATENT OFFICE.

DAVID C. LEE, OF DETROIT, MICHIGAN.

AUTOMATIC PRINTER FOR PAPER-ROLLS.

No. 887,730.

Specification of Letters Patent. Patented May 12, 1908.

Application filed January 28, 1907. Serial No. 354,547.

To all whom it may concern:

Be it known that I, DAVID C. LEE, a citizen of the United States, residing at Detroit, in the county of Wayne and State of Michigan, have invented a new and useful Automatic Printer for Paper-Rolls, of which the following is a specification.

This invention relates to printing attachments for paper rolls and has for its object to provide a comparatively simple and inexpensive device of this character capable of being quickly attached to or removed from the roll and by means of which an advertisement or other matter may be printed on the paper as the latter is unwound from the roll.

A further object of the invention is to provide the printing roller with spaced longitudinal bars having convex side walls and defining intermediate type-receiving recesses or grooves, said type being removably supported in position on the printing roller by frictional engagement with the convex walls of the grooves.

A further object is to provide means for yieldably supporting the printing roller in contact with the paper roll and means for permitting a limited rocking movement of the printing roller thereby to accommodate inequalities in the paper roll.

A still further object of the invention is to generally improve this class of devices so as to increase their utility, durability and efficiency.

With these and other objects in view the invention consists in the construction and novel combination and arrangement of parts hereinafter fully described, and illustrated in the accompanying drawings, it being understood that various changes in form, proportions and minor details of construction may be resorted to within the scope of the appended claim.

In the accompanying drawings forming a part of this specification: Figure 1 is a transverse sectional view of a printing attachment constructed in accordance with my invention showing the same in position on a paper roll. Fig. 2 is a perspective view of the printing attachment removed. Fig. 3 is a detail sectional view of one of the spaced disks.

Similar numerals of reference indicate corresponding parts in all of the figures of the drawings.

The improved device is principally designed for attachment to paper rolls and the like for printing an advertisement or other

matter on the wrapping paper as the latter is unwound from the roll, and by way of illustration is shown in connection with a paper roll of the ordinary construction in which 5 designates the roller-supporting frame and 6 the paper roll.

The attachment consists of a longitudinal bar or supporting member 7 to which are secured spaced plates or brackets 8 having their free ends extended beyond the adjacent longitudinal edge of the bar and bent laterally to form terminal eyes 9 for the reception of the roller supporting frame or yoke, indicated as a whole at 10.

The yoke 10 is provided with an intermediate off-set portion 11 and depending arms 12 the free ends of which are provided with terminal enlargements or bearings 13 in which is journaled the shaft 14 of the printing roller.

The printing roller consists of spaced disks or wheels 15 having their inner edges cut away at the periphery of the wheel and provided with spaced recesses or sockets 16 for the reception of the adjacent ends of the cylindrical connecting bars or rods 17.

The bars 17 are spaced apart to form intermediate grooves or recesses for the reception of the removable type 18, the latter being preferably formed of rubber or other yieldable material and clamped in position by frictional engagement with the convex walls of the rods 17, as best shown in Fig. 2 of the drawing.

Interposed between the disks or wheels 15 and resting on the shoulders 19 formed by the segmental recesses is a plate 19 preferably curved to conform to the contour of the disks and which forms a closure or bottom for the type-receiving grooves thereby to prevent the same from slipping through or between the longitudinal bars when the type is clamped in position on the printing roller.

Skidably mounted on the arms 12 of the roller supporting yoke are sleeves or collars 20 having sockets or recesses 21 formed therein for the reception of the trunnions of the inking roller 22, the latter being yieldably supported in engagement with the printing roller by means of coiled springs 23 interposed between the movable collars 20 and suitable fixed collars 24 carried by the arms 12 of the yoke.

The yieldable surface of the inking roller 22 preferably terminates short of the opposite ends thereof to form terminal flanges 25

which bear against the periphery of the disks or wheels 15 and serve to assist in centering the inking roller and also prevent the ink on the roller from coming in contact with the 5 wheels or disks and consequently smearing the paper when the device is operated.

The supporting member or bar 7 is secured to the roll supporting frame 5 by means of a bolt or similar fastening device 26 which extends through the bar 7 and roll supporting frame and is secured in position by means of a nut or similar clamping device 27, there being a washer 28 interposed between the bar 7 and the roll supporting frame so as to 10 permit a slight rocking or tilting movement of the bar 7 and thus permit the printing roller to conform to the paper roll should one end thereof be lower than the other which would necessarily give it a slight wobbling 15 motion.

Secured to the upper surface of the bar 7 are one or more coiled springs 29 having their intermediate portions extended to form arms 30 which bear against the lateral off-set portion 11 of the pivoted yoke or printing roller frame and serve to yieldably support the printing roller in engagement with the paper roll so that as the roller diminishes in size by reason of the removal of a portion of 25 the paper the printing roller and its associated parts will follow the contour of said 30 paper roll.

The inking and printing rollers are preferably inclosed in a suitable casing or housing 35 31 so as to protect the inking roller and type from dust and other foreign matter.

The opposite ends of the shaft 14 are preferably threaded and extended through the wheels or disks 15 for engagement with suitable clamping nuts 32 whereby the disk may 40 be removed and the bars 17 detached when the latter become broken or otherwise injured from constant use.

It will thus be seen that when a longitudinal pull is exerted on the free end of the 45 wrapping paper the inking roller by frictional engagement with said paper will revolve within the casing or housing and travel over the surface of the inking roller so that a further movement of the paper will cause 50 the type to press against the paper and thus leave the imprint of the type thereon.

From the foregoing description it is thought that the construction and operation of the device will be readily understood by 55 those skilled in the art and further description thereof is deemed unnecessary.

Having thus described the invention what is claimed is:

The combination with a paper roll frame, 60 of a supporting member mounted on the frame and provided with spaced brackets, a yoke pivotally mounted in the brackets and having an intermediate lateral off-set portion and its opposite ends provided with terminal bearings, a printing roller journaled in the bearings and having its opposite ends threaded, said printing roller being provided with spaced cylindrical rods forming type-receiving grooves, collars slidably mounted 65 on the yoke, an inking roller journaled in the collars, springs bearing against the collars for yieldably supporting the inking roller in engagement with the printing roller, means 70 for securing the supporting member in position on the roll frame, and springs carried by the supporting member and bearing against the off-set portion of the pivoted yoke.

In testimony that I claim the foregoing as 80 my own, I have hereto affixed my signature in the presence of two witnesses.

DAVID C. LEE.
